UNITED STATES PATENT OFFICE

152,158

DESIGN FOR A FOOD MIXER

Clarence Karstadt, Glen Ellyn, Ill.

Application January 11, 1947, Serial No. 136,095

Term of patent 14 years

(Cl. D44—1)

To all whom it may concern:

Be it known that I, Clarence Karstadt, a citizen of the United States, residing at Glen Ellyn, in the county of Du Page and State of Illinois, have invented a new, original, and ornamental Design for a Food Mixer, of which the following is a specification, reference being had to the accompanying drawing, forming a part thereof, in which:

Fig. 1 is a side elevational view of a food mixer showing my new design;

Fig. 2 is a rear elevational view;

Fig. 3 is a plan view; and

Fig. 4 is a front elevational view thereof.

I claim:

The ornamental design for a food mixer, as shown.

CLARENCE KARSTADT.
